US0D1109198S

(12) **United States Design Patent** (10) Patent No.: **US D1,109,198 S**
(45) Date of Patent: ** Jan. 13, 2026

(54) **LASER ENGRAVING MACHINE**

(71) Applicant: **Shenzhen TwoTrees Technology Co., Ltd.**, Shenzhen (CN)

(72) Inventors: **Zhitao Zeng**, Shenzhen (CN); **Rongpeng Huang**, Shenzhen (CN)

(73) Assignee: **Shenzhen TwoTrees Technology Co., Ltd.**, Shenzhen (CN)

(**) Term: **15 Years**

(21) Appl. No.: **29/987,654**

(22) Filed: **Jan. 25, 2025**

(51) LOC (15) Cl. **15-09**

(52) U.S. Cl.

USPC **D15/122**

(57) **CLAIM**

The ornamental design for a laser engraving machine, as shown and described.

DESCRIPTION

FIG. 1 is a first perspective view of a laser engraving machine showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the laser engraving machine that form no part of the claimed design.

1 Claim, 8 Drawing Sheets
